UNITED STATES PATENT OFFICE

GEORGE W. DENISON, OF CLEVELAND, OHIO, ASSIGNOR TO COMMON BRICK MANUFACTURERS' ASSOCIATION OF AMERICA, OF CLEVELAND, OHIO, A CORPORATION OF ILLINOIS

METALLIC INSERT FOR BRICK OR TILE STRUCTURES

Application filed January 31, 1929. Serial No. 336,476.

This invention relates to inserts for brick or tile structures and particularly to metallic inserts which are adapted to be inserted in a wall in place of a brick or other similar unit.

In certain communities it has become the practice for builders erecting houses for speculation to erect a frame structure and merely face it with brick, thus reducing the cost of construction, yet giving the house the appearance of an all brick house. Often a buyer is ignorant of the true construction of the house when he purchases the same.

To protect the purchaser a plan has been adopted by builders of genuine brick and tile houses to insert in the wall of a house constructed of brick or, in general, masonry of recognized and approved quality and workmanship some marker which will denote that fact.

An important object of my invention is to provide a device in connection with a wall by which the character of the inaccessible, unexposed portions of the wall structure may be identified throughout the life of the wall, and without recourse to removing any part thereof for examination.

A further object is to provide an identifying device which will replace a masonry unit and identify the interior wall construction, which device may be inserted in the wall at the time of building the same, or later.

A further object is to provide an identifying device of the character above set forth which will in no way impair the strength of the wall, and which will be pleasing in appearance.

A further object is to provide a metallic replacement which may have engraved thereon certain inscriptions, certifying as to the material and workmanship in the wall in which it is incorporated.

Further objects and features of the invention will become apparent from the following description relating to the accompanying drawing. The essential characteristics are summarized in the claims.

With the above objects in view, the invention resides in the structure hereinafter described and illustrated in the accompanying

drawing, in which Fig. 1 is a perspective view of a small section of a building wall showing my insert in the face of the wall; Fig. 2 is a perspective view of a preferred form of the insert; Fig. 3 is a plan view thereof, and Fig. 4 is a sectional view of the insert shown in Fig. 2, taken substantially along the line 4—4 on Fig. 2.

The insert is preferably made of a bronze or some other metal which will withstand corrosion for a great length of time. As shown, the insert comprises a substantially flat front portion 10 and two end portions 12 integrally joined to the portion 10 and projecting at right angles therefrom. The front face of the portion 10, substantially corresponds in area to the outer faces of the bricks or other units of which the wall is composed. It is to be understood that the insert is not limited to use in brick walls, but may be used in any other masonry construction, wherein it is desirable that the interior wall construction be identified. The portions 12 are preferably of a depth corresponding to the horizontal depth of a brick or other masonry unit which the insert replaces.

In order that the insert may be made comparatively light, while strong enough to withstand the usual pressures applied to a brick or the like, the portion 10 is flanged rearwardly at the top and bottom as at 14, and the portions 12 are flanged inwardly, toward each other, as at 16, the flanges 16 and 14 joining to provide in effect a box-like structure entirely open at one side, as opposite the portion 10, and also open at the top and bottom for a considerable extent. The flanges 14 and 16 serve to provide supporting surfaces for adjacent bricks or blocks, wide enough to support an intervening layer of mortar.

Obviously in some cases, the insert may be built into the wall at the time the masonry is laid up, the insert being then treated as an ordinary brick or block. If desired, the entire cavity which would otherwise be present within the confines of the portions 12 may be filled up with mortar, or a container may be placed within these cavities, carrying

whatever data it may be desired to preserve in the wall.

When the insert is to be placed in a wall already built up, one of the bricks or blocks of the wall is first removed and then an adequate supply of mortar placed in the resulting wall recess. Afterward the insert is shoved into place, squeezing the surplus mortar into the crevices surrounding the insert. Afterward the wall around the insert is pointed and the mortar left in the same condition as at the other bricks or blocks in the wall.

The primary purpose of the insert is to certify that the interior of the wall is of a certain type. For example, the wall may be solid masonry, or brick and tile, or brick and tile of a certain grade, etc. It also may be desirable to show the thickness of the wall. Obviously the front face of the portion 10 may be inscribed to certify to any of the above or other characteristics, such as the grade and quality of materials used in the wall. Preferably the characters are in relief as at 17 formed as by casting. Also it is desirable to indicate other memoranda, such as the serial number of the certification. Such data may be stamped on a raised panel, such as 18, at the time the insert is put into place.

30 I claim:

1. In a masonry building wall construction, a metallic building unit, comprising a front member and two end members integrally cast therewith, said members having a continuous flange at the top and bottom thereof; their height and length corresponding to the standard dimensions of the wall building units forming the outer part of the wall, and so placed in the wall and so formed as to have an outer exposed inscription face corresponding in area to the exposed face area of the outer building units in the wall, whereby the wall construction may carry a built in label portraying the character of the inaccessible unexposed portions of the wall structure.

2. In an outer building wall of masonry construction, a building unit in the form of a horizontal U having a front wall of a length and height corresponding to standard brick length and height and having on its outer face an inscription, and end walls corresponding to standard brick widths and heights, said hollow unit taking the place of a brick in the wall and being adapted to withstand the load which would be carried by such brick.

In testimony whereof, I hereunto affix my signature.

66 GEORGE W. DENISON.
